US00D412651S

United States Patent

[19]

Conrado et al.

[11] **Patent Number:** **Des. 412,651**[45] **Date of Patent:** ** Aug. 10, 1999[54] **CAN OPENER**

[75] Inventors: **Ann Marie Conrado**, Chgo, Ill.; **Lorens G. Hlava**, Clinton, Mo.; **Bart Massee**; **William Webb**, both of Chicago, Ill.

[73] Assignee: **The Rival Company**, Kansas City, Mo.

[**] Term: **14 Years**

[21] Appl. No.: **29/081,786**

[22] Filed: **Jan. 9, 1998**

[51] **LOC (6) Cl.** **07-99**

[52] **U.S. Cl.** **D8/36**

[58] **Field of Search** D8/33-43, 18, D8/19; 30/400-443; 81/3.07-3.49; 7/151-156

[57] **CLAIM**

The ornamental design for a can opener, as shown and described.

DESCRIPTION

FIG. 1 is a perspective view of a can opener showing our new design;

FIG. 2 is a left side view thereof;

FIG. 3 is a rear view thereof;

FIG. 4 is a front view thereof;

FIG. 5 is a right side view thereof;

FIG. 6 is a bottom view thereof; and,

FIG. 7 is a view of the invention in a retracted or closed state.

The top of the can opener is plain and unornamented.
